UNITED STATES PATENT OFFICE.

EDWIN WEESMAN, OF QUINCY, MASSACHUSETTS.

PORABLE CAMP-STOVE.

1,178,366.

Specification of Letters Patent.

Patented Apr. 4, 1916.

Application filed July 26, 1915. Serial No. 41,934.

To all whom it may concern:

Be it known that I, EDWIN WEESMAN, a citizen of the United States, residing at Quincy, in the county of Norfolk and State of Massachusetts, have invented new and useful Improvements in Portable Camp-Stoves, of which the following is a specification.

The invention relates to a stove, and more particularly to the class of portable camp stoves.

The primary object of the invention is the provision of a stove of this character wherein wood alcohol can be used as a fuel for cooking purposes, the stove and fuel reservoir being novel in construction so as to assure perfect combustion at the burner and the proper feed of the fuel thereto.

Another object of the invention is the provision of a stove of this character wherein the fuel can be fed under pressure to the burner, the said stove being readily portable so that it may be conveniently carried from place to place, and thereby making it handy for camping purposes.

A further object of the invention is the provision of a stove of this character which is simple in construction, thoroughly reliable and efficient in use, strong, durable, and inexpensive in manufacture.

With these and other objects in view, the invention consists in the construction, combination and arrangement of parts as will be hereinafter fully described, illustrated in the accompanying drawings, and pointed out in the claim hereunto appended.

In the drawings:—Figure 1 is a side elevation of a stove constructed in accordance with the invention. Fig. 2 is a vertical longitudinal sectional view through the burner. Fig. 3 is a vertical longitudinal sectional view through the reservoir for the fuel. Fig. 4 is a top plan view thereof. Fig. 5 is a top plan view of the burner. Fig. 6 is a sectional view on the line 6—6 of Fig. 3.

Similar reference characters indicate corresponding parts throughout the several views in the drawings.

Referring to the drawings in detail, the stove comprises a reservoir 10, preferably in the form of a tank open at its upper end, and has fitted therein a pressure piston 11 provided at its periphery with a groove 12 in which is seated a tension ring 13 working against packing ring 14 concentrically dis-

posed relative thereto, while fixed to the piston 11 and overlying the rings 13 and 14 is an annulus or flange ring 15 which is bolted or otherwise secured to the said piston and retains the tension and packing rings 13 and 14 in the groove 12 therein. Adjustably threaded in the piston 11 are tension screws 16 which act upon the tension ring 13 for regulating the same.

Bridging the upper open end of the reservoir 10 is a cross strap 17 formed with hook terminals 18 for detachable engagement with diametrically opposed lugs 19 formed on and projecting laterally from the body of the reservoir 10, and passed through the strap 17 centrally thereof is a lift stem or rod 20 which is detachably engaged centrally in the piston 11 and has formed on its outer end a knob 21 so that the piston 11 can be raised within the reservoir 10 after the lowering thereof in a manner presently described.

At opposite sides of the lift stem 20 and adjustably threaded in the cross strap 17 are adjusting stems 22 provided at their outer ends with knobs 23, while at their inner ends are formed heads 24 against which work coiled expansion springs 25, the same working against the piston 11 for moving the same downwardly within the reservoir or tank to exert pressure upon the body of liquid fuel contained therein, it being seen that upon adjustment of the stems 22 the tension of the springs 25 can be varied, thereby regulating the pressure exerted by the piston working within the reservoir.

Tapped in the reservoir at its bottom is an outlet nipple 26 to which is connected a feed tube 27, the same being also connected to a burner stem 28 integral and communicating with the crossed burner tubes 29 which are fitted at their outer free ends with removable plugs 30 to permit the cleaning thereof, the tubes being formed with orifices 31 as usual for the ignition of the fuel for the issuance of the flames from the burner. The burner stem 28 is passed centrally through the bottom of a substantially hopper or dish-shaped burner pan or casing 32 supported upon legs 33 and having mounted thereon a circular rim 34 containing a rest spider 35 on which is adapted to be placed the cooking utensils so that the same will be disposed in the path of the flame or flames from the burner.

The outlet nipple 26 tapped in the reser-

110

voir 10 is provided with a pressure gage 36 so that the pressure within the reservoir can be determined when inspecting the gage.

It will be apparent that when the cross strap 17 is detached from the lugs 19 the piston 11 with the stems 20 and 22 can be removed from the reservoir 10 for the convenient filling of the same with liquid fuel, preferably wood alcohol, which is adapted to be delivered to the burner under pressure.

From the foregoing description, taken in connection with the accompanying drawings, the construction and manner of operation of the device will be clearly understood, and therefore a more extended explanation has been omitted.

What is claimed is:—

The combination with a burner, of a cylin-

der having a valved communication with the burner, diametrically opposed lips on the cylinder, a bridge-piece having a hook end detachably engaging the lips, said bridge-piece having threaded and non-threaded apertures, screws engaged in the threaded apertures, a sliding stem working in the non-threaded apertures, a piston within the cylinder and detachably connected with the sliding stem, and compression springs resting upon the piston and acted upon by the screws.

In testimony whereof I affix my signature in presence of two witnesses.

EDWIN WEISSMAN.
